UNITED STATES PATENT OFFICE.

RUFUS KING, OF PLAINVILLE, MASSACHUSETTS, ASSIGNOR TO BUGBEE & NILES CO.,
OF NORTH ATTLEBORO, MASSACHUSETTS.

WATCH-BRACELET CLASP.

Application filed December 8, 1927. Serial No. 238,544.

This invention relates to certain new and useful improvements in watch bracelet clasps, and the primary object thereof is to provide a clasp of this type which when released increases the diameter of the bracelet to a considerable range, as compared with the prior art, thereby to enable the bracelet to be more easily and readily removed from the arm.

10 A further object of the invention is to provide a clasp of this type in which the parts when in closed or contracted position are compactly related so as to minimize the space and particularly the thickness of the clasp.

15

In the drawings:—

Figure 1 is a plan view of the clasp in closed or folded position of the parts;

Figure 2 is a side edge elevation;

20 Figure 3 is a rear plan view;

Figure 4 is a section on line 4-4 of Fig. and

Figure 5 is a view similar to Figure 1, showing the parts in open or extended position;

Figure 6 is a rear plan view of Fig. 5 and

Figure 7 is a section on line 7-7 of Figure 3.

30 In proceeding in accordance with the present invention a front or face member 1 is employed which is provided with parallel sides 2 that extend outwardly from the front member and are provided with a

35 series of perforations 3. One end A of the watch bracelet is provided with a clip 4 that carries a pin 5 which latter is engageable in a selected pair of the perforations 3 of the side flanges 2 of the front member, thus enabling to adjust the bracelet so as to fit the

40 thereby to adjust the bracelet so as to fit the wrist of the wearer as desired. The opposite end B of the bracelet is likewise provided with a clip 6 carrying a pin 7 the pin being movably received in ears 8 formed on a member 9. The member 9 is hinged at 10

45 member 9. The member 9 is hinged at 10 to a back forming member 11, and the back forming member 11 in turn is hinged at 12 to a member 13 which latter has its inner end bent to form a knuckle 14 in which a pin 50 15 is received. The pin 15 as shown in

50 13 is received. The pin 15 as shown in Figures 4 and 6 is journaled in the side flange 2 of the front member 1 at one end of the latter. The member 13 is formed with an opening 16 of substantially rectangular 55 form the opposed end walls of which open-

ing constitutes a keeper for a pair of spring fingers 17 that are carried by the back member 11. As shown in Figure 7 of the drawings, the fingers 17 are curved and are adapted to be snapped into engagement with the opposed end walls of the opening 16. 60

In operation, it will be noted that in the extended position of the parts shown in Figures 5 and 6, considerable space exists between the two ends A and B of the bracelet, which permits the latter to be easily, quickly and conveniently removed from the arm of the wearer. To close the parts, the member or section 9 is folded against the rear face of the back member 11 and then the members 9 and 11 are moved about the hinge 12 and pin 15 to bring the member 13 against the clip 4 as shown in Figure 4, whereupon the member 11 is moved inwardly toward the front member 1 and its fingers or clasp members 17 are moved into the keepers 16 and are thereby snapped into engagement with the keeper, thus latching the parts in the position shown in Figures 1-4. By referring to Figure 4 it will be noted that the various hinged or pivoted sections 9, 11 and 13 are compactly foldable and when housed in the front member 1 occupy a minimum of space with the result that all of the parts afford a clasp structure of minimum thickness. In addition it will be noted that in order to open or extend the bracelet it is merely necessary to disengage the clasps 17 from its keeper, and owing to the members 9 and 11 projecting beyond the end of the front member adjacent to the clasp, the latter can be easily and quickly disengaged, following which the parts can be readily extended by merely pulling on the bracelet ends A and B.

Having thus described my invention what I claim as new and desire to secure by Letters Patent is:—

1. In a wrist watch bracelet clasp, a front member, means to connect one end of a bracelet to one end of the member, a second member having a keeper, means to pivotally connect one end of the second member to the opposite end of the front member, a back member pivotally connected at one end to the opposite end of the second member, latching means carried by the back member for snapping engagement with the keeper of the second member, a fourth member pivotally connected at one end to the 100 105 110

opposite end of the back member; and means to pivotally connect the other end of a bracelet to the opposite end of the fourth member, said second and fourth members being movable so as to be disposed between the front and back member in folded position of the parts.

2. In a wrist watch bracelet clasp, a front member, means to connect one end of a bracelet to the front member, a back member, connecting means for said back member movably secured to said front member and to said back member so as to be foldable to lie between said members, means connecting the opposite end of the bracelet to the back member and also foldable to lie between said members, and means to latch the back member against movement.

3. In a wrist watch bracelet clasp, a front member, means to connect one end of a bracelet to the front member, a back member, means to movably connect one end of the back member to the front member and foldable to lie between said members, means to latch the back member to said means for connecting the members, and means to connect the opposite end of the bracelet to the back member, said last named means being foldable to lie between said members and when folded lying in substantially the plane of the said means for connecting the members.

4. In a wrist watch bracelet clasp, a front member, means to connect one end of a bracelet to the front member, a back member, connecting means connected to the front member, and to the back member and foldable to lie between said members adjacent one end thereof, and connecting means connected to the back member and to the opposite end of the bracelet and foldable to lie between said members adjacent the opposite end thereof.

5. In a wrist watch bracelet clasp, a front

member, means to connect one end of a bracelet to the front member, a back member, connecting means connected at one end to one end of the back member and also connected to the front member so as to be foldable to lie between said members, and connecting means connected at one end to the opposite end of the back member and to the opposite end of the bracelet and foldable to lie between said members.

6. In a wrist watch bracelet clasp, a front member, means to connect one end of a bracelet to the front member, a back member, connecting means connected at one end to one end of the back member and also connected to the front member so as to be foldable to lie between said members; and connecting means connected at one end to the opposite end of the back member and to the opposite end of the bracelet and foldable to lie between said members, each of said connecting means being disposed in substantially the same plane when in folded position.

7. In a wrist watch bracelet clasp, a front member, means to connect one end of a bracelet to the front member, a back member, connecting means connected to the front member and to the back member and also connected to the front member so as to be foldable to lie between said members adjacent one end thereof, connecting means connected to the back member and to the opposite end of the bracelet and foldable to lie between said members adjacent the opposite end thereof, each of said connecting means being spaced from each other in folded position thereof, a keeper on the first named means, and latching means carried by the back member and engageable with said keeper.

In testimony whereof I have signed my name to this specification.

RUFUS KING
